UNITED STATES PATENT OFFICE.

WILLIAM F. LINSTEDT, OF PLYMOUTH, WISCONSIN.

POWER-DRIVEN CAN OPENER.

Application filed February 28, 1924. Serial No. 695,817.

To all whom it may concern:

Be it known that I, WILLIAM F. LINSTEDT, a citizen of the United States, residing at Plymouth, in the county of Sheboygan and State of Wisconsin, have invented certain new and useful Improvements in Power-Driven Can Openers, of which the following is a specification.

This invention relates to power driven can openers and particularly to a machine having power operated means for holding and rotating a can, while a rotary knife operated by said power means severs the top portion therefrom.

An object of the invention is to provide a support of suitable form mounting a rotatable can receiving head, with which is associated a rotatable cutting member, each having suitable connections with a source of power carried by the frame, adapted to be rotated relative to one another for severing the top of a can from the body portion thereof.

Another object of the invention resides in providing a can opener wherein a rotatable can receiving member, and an associated rotatable cutting member are mounted on a frame for a limited relative movement to receive a can, the relative movement of the can receiving member to the cutting member permitting the movement of said member toward the cutting member by a manually operated lever, to force a co-operation between said members, so that the cutting blade will sever the top portion of the casing from the body.

The invention also comprehends other objects and improvements in the details of construction and arrangement of parts which are more clearly pointed out in the following description and claims directed to a preferred form of the invention, it being understood, however, that variations in the arrangement and specific construction of these parts may be made without departing from the scope of the appended claims.

In the drawings, forming a part of this application:

Figure 1 is a side elevation of a can opener forming the subject of this invention, mounted on a table or the like.

Fig. 2 is an end elevation of the invention as shown in Figure 1.

Figure 3 is a plan view thereof.

Figure 4 is a detail sectional view taken on the line 4-4 of Figure 2.

1 indicates a table, such as that used in a hotel or boarding house kitchen, wherein it is desired to quickly and conveniently open large numbers of cans of material, and on which the can opener constructed according to this invention is mounted.

A frame of substantially U-shaped structure is indicated at 2, having the base portion 3, secured to the table by screws or any other suitable means, and the legs or uprights 4 extending upwardly therefrom and connected adjacent the upper ends by the connecting lug 5, the upper ends of the uprights 4 being formed with bearings for receiving the power shaft 6, which is rotatably mounted in the bearing. One end of the shaft adjacent one of the uprights 4 is provided with a disc 7, receiving an operating handle 8, by which the shaft may be rotated, or if desired, a belt from a suitable motor or any other suitable source of power may be passed over the periphery of the disc 7. The other upright 4 is provided with pairs of aligned vertical projections 9 and 10 respectively, the projections 9 being spaced from the upper ends of the uprights, while the projections 10 are at the lower end thereof.

Projections 9 and 10 are formed adjacent the uprights 4, with bearings for a cutter shaft 11 extending vertically through the projections and rotatable in the bearing, and provided at the upper end with a bevelled gear 12 meshing with a corresponding bevelled gear 13 on the end of the power shaft 6. The lower end of the cutter shaft below the pair of projections 10 is provided with a cutter head 14 carrying the annular cutting blade 15.

A member 16 is pivoted at 17 between the pair of projections 9 and is provided with lateral extensions from the upper smaller ends thereof as indicated at 18, forming bearings for rotatably receiving a shaft 19, provided at the upper end with a spur gear 20 meshing with a spur gear 21 mounted on the cutter shaft 11 adjacent the bevelled gear 12, for rotating the shaft 19 in a direction opposite to the cutter shaft 11 for a purpose which will presently appear. The lower end of the shaft 19 projects below the end of the member 16, and is provided with a head 22 having an annular can receiving flange 23, on the lower free end thereof which is positioned slightly above the annular cutting member 15 car-

ried by the head 14. The lower end of the member 16 is freely movable between the projections 10 and is engaged by the hand lever 24 pivotally mounted at 25 between 5 the outer ends of the projection 10, the ends of said lever being adapted to engage the member 16 in order to force the head 22 toward the cutter head 14. A spring member 26 is positioned between the uprights 10 4 and the member 16 and adapted to normally force the member 16 outwardly on its pivot 17, to move the head 22 away from the cutting head 14.

In the operation or use of this machine 15 for cutting the tops from the cans, the end of the can which is usually provided with an upwardly projecting flange beyond the end wall thereof, as clearly indicated in Figure 4, is positioned so that the flange 20 will project upwardly beyond the flange 23 of the can receiving member or head 22 so that the former will engage the inner edge of this flange of the can, the lower face of the plate seating against the end wall of 25 the can body. Upon the rotation of the operating shaft 6, a corresponding rotating movement will be imparted to the shafts 11 and 19 for rotating them in opposite directions as above described, and at which time, 30 a movement of the lever 24 about its pivot will force the member 16 inwardly toward the upright 4, so that the plate 23 will force the can toward the cutting head 14 so that the annular cutting member 15 will cut the 35 can in the rotation thereof slightly below the end as clearly shown in Figure 4, the operator holding the body of the can below the cutter and removing it as soon as one complete rotation has been completed, 40 which is sufficient for severing the top of the can from the body.

From the above description, it will be clearly seen that a simple and novel form of power driven can opener has been provided, wherein the upper end of the can body may 45 be quickly severed from the main portion thereof in order that the contents of the can may be forced from the can.

What is claimed is:

A can opener including a frame having 50 uprights, a power shaft rotatably mounted in said uprights, one of said uprights having upper and lower pairs of projections, a cutter shaft rotatable in said projections adjacent the uprights, a cutter head having 55 an annular cutting blade mounted on the lower end of said cutter shaft, a power transmitting connection between the upper end of the cutter shaft and the power shaft, a member pivoted between the upper projection and movable between the lower projections, a shaft rotatably mounted in said member having driving connections with said cutter shaft for rotating said shaft in a direction opposite to said cutter shaft, 60 a can receiving head mounted on the lower end of said last mentioned shaft, an operating lever pivotally mounted between said lower projection for moving said member toward the cutter head, whereby the can 65 will be forced by said can receiving head against the annular cutting blade of the cutter head for severing the end of the can from the body thereof in the rotation of said shaft and a spring interposed between 70 said one upright and said pivoted member for exerting an awkward stress on the lower end of the member.

In testimony whereof I affix my signature.

WILLIAM F. LINSTEDT.
